(57) **CLAIM**

The ornamental design for a fork receiver of a forkliftable tilt truck frame as shown and described.

DESCRIPTION

FIG. 1 is a top front perspective view of a fork receiver of a forkliftable tilt truck frame showing our new design;
FIG. 2 is a bottom rear perspective view of FIG. 1;
FIG. 3 is a front side elevation view of FIG. 1;
FIG. 4 is a left side elevation view of FIG. 1, in which the right side elevation view is a mirror image thereof;
FIG. 5 is a rear side elevation view of FIG. 1;
FIG. 6 is a top plan view of FIG. 1; and,
FIG. 7 is a bottom plan view of FIG. 1.

The broken line shown in the figures are for the purpose of illustrating the environment and form no part of the claimed design.

The fork receiver of a forkliftable tilt truck frame is shown with symbolic breaks in its length. The appearance of any portion of the article between the break lines form no part of the claimed design.
